UNITED STATES PATENT OFFICE.

CLARENCE KENYON, JR., OF NEW YORK, N. Y.

OVERSHOE.

Application filed July 13, 1927. Serial No. 205,333.

My invention relates to a new and improved form of flexible rubber or overshoe.

One of the objects of my invention is to provide a rubber which will be sufficiently flexible to enable it to be folded into a very small space and which will have sufficient flexible reinforcement to enable it to assume a suitable predetermined shape.

Another object of my invention is to provide a flexible overshoe made throughout of flexible and unfilled rubber, and having flexible reinforcement, so that the overshoe can be stretched to correspond to several sizes.

Another object of my invention is to provide an overshoe having the characteristics above mentioned and which can be made simply and cheaply.

Other objects of my invention will be set forth in the following description and drawings which illustrate a preferred embodiment thereof, it being understood that the above general statement of the objects of my invention is intended to generally explain the same and not to limit it in any manner.

Figure 1 is a perspective view showing the improved overshoe.

Figure 2 is a bottom plan view, parts of the outer layers of the overshoe being shown broken away to illustrate the inner construction.

Figure 3 is a central sectional view.

Figure 4 is a sectional view on the line 4-4 of Figure 3.

Figure 5 is a sectional view on the line 5-5 of Figure 3.

Figure 6 is a view of the pattern used for forming the upper of the overshoe.

Figure 7 illustrates the pattern used for forming or cutting the outer sole of the overshoe.

Figure 8 shows the pattern used for forming or cutting the inner sole of the overshoe.

Figure 9 illustrates the pattern used for cutting the upper and longer reinforcing strip for the opening of the overshoe.

Figure 10 illustrates a similar pattern for forming and cutting the corresponding lower and shorter strip.

As shown in Figures 1-5 inclusive, the rubber 10 has an upper portion 10^a and an upper opening 10^b. As shown in Figure 6, the upper 10^a has a tapered front portion terminating in a rounded point, tapered wings 16 and 17, the opening 10^b extending substantially to the rear of the pattern sheet,

and rear portions 21 which are inclined to the axis of the pattern strip, said rear portions or wings 21 terminating in edges 20 which form an obtuse angle with each other, 60 and which make an angle of more than 90° with the axis or central longitudinal line of the pattern sheet. The upper 10^a is bent into the shape shown in Figures 1-3 for example, so that the intermediate wings 16 65 and 17 are folded under to form the arch portion of the overshoe. The front of the upper 10^a is connected to an inner sole 11 by means of a rubber strip 15 which has an angular lateral contour as shown in Figure 70 4. This strip 15 is an extension of the inner sole 11.

A reinforcing strip 14 is provided at the toe of the overshoe.

The outer sole 12 is also connected to the 75 upper 10^a by means of an outer strip 13 which is an extension thereof.

The sole portion of the overshoe comprises two thicknesses of rubber sheeting, save for the toe thereof, where it is reinforced by the 80 third strip 14.

However, the arch portion of the overshoe comprises four thicknesses of rubber sheeting, namely, the inwardly bent wings 16 and 17 of the upper sheet which are bent under 85 each other so that they overlap, as shown in Figure 5, and the arch portions of the sheets 11 and 12. Hence, the arch portion of the overshoe has greater rigidity than the other parts thereof, although it is to be understood 90 that said arch portion is preferably stretchable and flexible.

The upper or longer edge of the opening 10^b is reinforced by a strip 18 and the lower or shorter edge of the opening 10^b can be 95 reinforced by a strip 19. The ends 20 of the upper sheet are cemented to each other.

Because of the relative rigidity of the arch portion, the end portion of the overshoe can be readily folded about the said arch portion, and the overshoe may then be rolled or bent to occupy a very small space. I prefer that all the parts of the overshoe above mentioned should consist of sheets of flexible rubber without any filling, these being 105 connected to each other by cementing or any other suitable means.

Due to the fact that the parts of the rubber are made of sheets of unfilled rubber, that is, of pure gum sheeting, each and every 110 part of the overshoe is readily stretchable so that it can be used on shoes of varying sizes.

However, I do not limit myself to the use of unfilled rubber, because my invention covers the use of any form of rubber which is flexible, or flexible and stretchable.

5 I have shown a preferred embodiment of my invention but numerous changes and omissions may be made without departing from the spirit thereof.

I claim:—

- 10 1. An overshoe comprising an upper having lateral wings intermediate the ends thereof, said lateral wings being inwardly bent and overlapped, and inner and outer sole portions connected to the said upper, said inner and outer sole portions extending 15 into the arch portion of the overshoe.
- 15 2. For use in an overshoe, an upper sheet comprising a tapered front portion, lateral

wings extending outwardly from said front portion, and a rear portion consisting of 20 strips separated by an opening which extends into the central part of the said upper sheet.

3. An upper sheet according to claim 2 in which the said opening is rearwardly 25 tapered.

4. An overshoe which is flexible and stretchable throughout and having a sole portion and an arch portion respectively composed wholly of layers of stretchable 30 rubber, said arch portion having more layers of stretchable rubber therein than said sole portion, so that substantially said entire arch portion is stiffer than said sole portion.

In testimony whereof I affix my signature.

CLARENCE KEN YON, JR.
